DESIGN FOR A FOUNTAIN PEN SECTION OR SIMILAR ARTICLE

Solomon M. Sager, Chicago, Ill.

Application January 20, 1943, Serial No. 109,306

Term of patent 14 years

To all whom it may concern:

Be it known that I, Solomon M. Sager, a citizen of the United States and a resident of the city of Chicago, in the county of Cook and State of Illinois, have invented a new, original, and ornamental Design for a Fountain Pen Section or Similar Article, of which the following is a specification, reference being had to the accompanying drawing, forming a part thereof.

On the drawing:

I claim:

The ornamental design for a fountain pen section or similar article, as shown.
SOLOMON M. SAGER.
